UNITED STATES PATENT OFFICE.

AXEL E. OSTERBERG AND GUSTAF A. OBERG, OF NORWAY, MICHIGAN.

TWINE-HOLDER.

1,307,062.

Specification of Letters Patent. Patented June 17, 1919.

Application filed April 29, 1918. Serial No. 231,343.

To all whom it may concern:

Be it known that we, AXEL E. OSTERBERG, a citizen of the United States, and GUSTAF A. OBERG, a subject of the King of Sweden, 5 both residing at Norway, Dickinson county, Michigan, have invented certain new and useful Improvements in Twine-Holders, of which the following is a specification.

Our invention relates to devices for supporting cones or balls of twine over a shop or store counter, and has particular reference to supports equipped with means for automatically pulling up clear of the counter or shelf the loose end of said twine. The 15 object of the present invention is to provide a more stable holder than heretofore provided, and one resting on a post or pedestal that may be firmly mounted on a counter or shelf at any convenient point along 20 same instead of being suspended from a ceiling. Another object is to provide a holder which may be inexpensively made out of wood in suitably ornamental designs, which conceals the retracting weight, and 25 which embodies other features and advantages that cannot be derived from wire-work construction and the like.

With the above-named objects in view our invention consists in the novel construction, 30 combination and arrangement of parts, all as hereinafter described in detail, illustrated in the accompanying drawing and more particularly pointed out in the appended claims.

In the drawing—

35 Figure 1 is a perspective view partly in section of a holder embodying our invention.

Fig. 2 is a vertical half, partly in section and partly broken away, of same, with a 40 modification.

In the several views 2 represents a hollow post or pedestal, which is adapted to be made out of wood and in two substantially identical longitudinal sections 3 and 3', one 45 of which is shown in Fig. 2 with the interior groove. The sections 3 and 3' may be secured together in any suitable manner, and, if preferred, the post may be one piece and bored longitudinally in the manner herein- 50 after shown. From the top of the post 2 to a point near its lower end extends a bore 4 one-half of which may be in the form of a groove or channel in each of the sections 3 and 3'. The lower end of the post 2 is in 55 the form of a reduced or tenon portion 5

and the latter is engaged with a mortise 6 in a base-plate or foot portion 7 provided with screw holes or other suitable fastening means. The upper end of the post 2 is formed into a truncated cone, or core-portion, 9 that is adapted to enter or engage the usually tapered hole in the center of a cone of twine 10 or to engage and support a tapered socket portion 11 on a cup or vessel 12 adapted to loosely contain a ball of 60 twine 13. The twine-containing vessel, or the ball or cone of twine is further supported by a platform 14 which has a mortise and tenon joint connection with the post 2, as shown in Fig. 2. Transversely through the 70 post 2 and below the level of the platform 14 is a rectangular opening 15, and transversely through the section 3' at the bottom —16— of the bore 4 is an opening 17 which is a trifle larger than a twine-retracting weight 18 so that the weight may, when desired, be removed through said opening 17. At intervals along the post 2 and between the openings 15 and 17 are a series of 75 transverse bores 19, 20, 21, 22, and 23 adapted to receive an adjustable stop-pin 24 which limits the downward movement of the weight 18 in the passage 4. On the bottom of the upper transverse opening 15 is mounted a block 25 having in one end a groove 26 80 in which is mounted an anti-friction roller 27 and an eye or staple 28. On the opposite end of the block 25 is an eye or staple 28'. 85

When the conical form of wound twine is employed the upper end of the passage 90 or bore 4 is extended above the cone 10 by means of a hollow spindle or tube 29. The lower end of this extension 29 is reduced to fit into the opening 4 and to provide a shoulder which preferably is of rectangular 95 form and provides a seat in the form of a rectangular recess 30 (Fig. 2) or enlarged upper end of the passage 4. The exact details of the joint between the extension 29 of the conical spindle 9 are not 100 material and may be varied in any suitable manner. From the platform 14 extends an arm 31 which may be a heavy piece of wire. The inner end of this arm is bent into a lug 32 tightly held in a shallow bore 33 in the 105 under-side of the platform 14. The arm is further secured by means of a staple 34 or other suitable fastening means. On the arm 31 between the ends thereof is suspended a loop or eye 34, which may, as 110

shown, be a piece of wire twisted about the arm and looped. On the outer or free end of said arm is another similar eye or loop 35.

From the cone 10 a length of twine 36 is passed downwardly through the spindle 29 and thence through the opening 4, the opening 15, the eye 28' and downwardly in the passage 4 through an eye 37 in the upper end of the weight 18, whence the cord extends upwardly over the roller 27, through the loop or staple 28 and finally through the eyes 34 and 35. In the Fig. 2 modification the length of twine 36 passes from the ball 13 to the top of the conical spindle 9, from which, in this figure, the extension 29 is omitted. Otherwise the cord arrangement is the same in Figs. 1 and 2. The arm may be projected to any desired extent and in any desired direction from the platform 14 and away from the post 2.

The weight 18 is of elongated form, as shown, and as it is suspended from its longitudinal axis and free of side attachments it is not liable to bind or stick in a smooth bore 4. The extreme end of the length of twine 36, or the freely suspended portion, is separately designated by the numeral 38. When the operator pulls downward on this end the weight 18 is drawn up so that its eye 37 is aligned or registers with the eyes 28 and 28' so that the run of twine between these eyes is straight. When a salesman after wrapping a package and after having broken off the necessary piece of twine, releases the remaining end 38 this will be drawn up by the weight 18 falling

and the extent or height to which said end is drawn is determined by the position of the pin 24. The block 25 is shown held in place in the opening 15 by means of a pin 39 which extends through the post 2 and said block. If flexibility at this point is desired the block may have a slight pivotal movement on said pin.

We claim as our invention—

1. The combination of a pedestal or post having a longitudinally passing bore or opening therewithin, of a hollow core or hub portion at the upper end thereof adapted to support a twine package, an arm extending from said pedestal or post, a weight with an eye thereon in said bore or opening, and guides for a run of twine which guide a length of twine from a cone and the like of twine through said hollow core to the end of said arm.

2. The combination of a hollow pedestal having a foot thereon adapted to be secured to a counter and the like, of a weight movable within said pedestal, a hollow support on top of said pedestal for supporting a twine package and guiding a run of twine therethrough, a laterally extending arm, and guide loops or eyes along said post and arm and on said weight whereby a run of twine is led from the interior of said cone to a point below said arm and to said weight and thence to the end of said arm.

In testimony whereof we have hereunto subscribed our names.

AXEL E. OSTERBERG.
GUSTAF A. OBERG.
